UNITED STATES PATENT OFFICE.

EDWIN S. JARRETT, OF NEW YORK, N. Y.

MIXING-CONTAINER.

1,332,985.

Specification of Letters Patent. Patented Mar. 9, 1920.

Application filed September 12, 1919. Serial No. 323,374.

To all whom it may concern:

Be it known that I, EDWIN S. JARRETT, a citizen of the United States, residing at New York, N. Y., have invented certain new and useful Improvements in Mixing-Containers, of which the following is a clear, full, and exact description.

My invention relates to a method and apparatus whereby substances may be mixed or chemical compounds formed out of contact with the outer air. To this end I provide a container or a plurality of containers within each of which is placed a substance which is to enter into the mixture or compound, the container or containers being then hermetically sealed. In this condition they are placed within another container which is then hermetically sealed and means are provided whereby the substances are allowed to mix or form a chemical combination by any suitable means but preferably by a mechanical manipulation of the outside container. In the drawings accompanying this specification, I have shown a practical form of apparatus for carrying out my invention, and in said drawings—

Figure 1 is a sectional view of one form of apparatus in which three inner containers are employed;

Fig. 2 is a sectional view on the line 2—2, Fig. 1;

Fig. 3 is a sectional view of a form the apparatus may take when only two inside containers are employed; and

Fig. 4 is a section upon the line 3—3 of Fig. 3.

Referring to the drawings, 1 represents an outside container within which is situated one or more inner containers 2. These inner containers are designed to receive a charge of any selected substance and after being filled with such substance are hermetically sealed and placed within the outer container 1. These inner containers may be of metal, glass celluloid or pyralin or other substances which may be readily ruptured or penetrated by a sharp point or otherwise, or by distortion, such as bending or twisting. The outer container is preferably made of metal or of such material which can be distorted by squeezing or twisting or otherwise without being ruptured, and when a chemical compound is formed within said container by the substances contained in the inner containers, the material of the outer container must be of sufficient strength to

withstand any force generated by the chemical reactions which may take place. When but one inner container is employed, the substance with which its contents is to mix is placed in the outside container.

In order that the inner containers may be readily ruptured, I have shown as one means for accomplishing this a number of projections or points such as 5, extending from the inner wall of the outside container, these points acting to penetrate the inner containers when the pressure is properly exerted on the walls of the outside container. Preferably, I pack the spaces between the inner containers and the outer container with any suitable substance, such as cotton or the like, to prevent premature or undesired rupture of the inner containers which might result from a fall or accidental blow, such packing being shown at 4 in the figures.

It is, of course, understood that the size of the containers is important only to the extent that they must be of such size as to contain each its predetermined quantity of selected substance. Also, the shape of the different containers may be varied to suit different conditions depending upon the adoption of any one of the different methods which might be used in a complete apparatus. Preferably, the outer container may be in the form of a cylinder having rounded ends. The inner containers may be similarly shaped, or they may be spherical.

The outer container will ordinarily contain some air in the spaces unoccupied by the packing and by the substance contained therein in case of use of only a single inside container; but this air will not be objectionable, as its presence may be allowed for in some cases. If, however, this air or any ingredient thereof is undesirable in any case, it is of course obvious that its place may be taken by other gases which are not objectionable.

What I claim as new is—

1. In a mixing container, an outer and substantially air-tight but readily distortable container, a sealed and readily rupturable container within the same, and means constructed and arranged to rupture the inner container by a distortion of the outer container insufficient to rupture the latter.

2. In a mixing container, an outer readily distortable container, a plurality of sealed and readily rupturable containers within the same, and means constructed and arranged

to rupture the inner containers by a distortion of the outer container insufficient to rupture the latter.

3. A method of producing mixtures of substances out of contact with the air, which consists in providing an outer and substantially air-tight but readily distortable container which contains an ingredient of the mixture, and a sealed and readily rupturable container within the same, said inner container containing another ingredient, and rupturing the inner container by distorting the outer insufficiently to rupture the latter.
4. A method of producing a mixture out of contact with the air, which consists in providing an outer and readily distortable container, and a plurality of sealed and readily rupturable containers within the same, each one of said inner containers con-
- 5

taining an ingredient of the desired mixture, and mixing the same by rupturing the inner containers by distortion of the outer container insufficiently to rupture the latter.

5. In a mixing container, an inner container and an outer container, each hermetically sealed and each containing a substance to form a part of a compound or mixture, said inner container formed of material that may be readily ruptured, and means for rupturing said inner container at will by a distortion of the outer container, thereby bringing about a mixture of the said substances within the outer container while the outer container remains unruptured.

Signed at New York city, New York, this 2nd day of September, 1919.

EDWIN S. JARRETT.
